UNITED STATES PATENT OFFICE.

EDWIN N. LIGHTFOOT, OF NEW YORK, N. Y., ASSIGNOR TO THE CUTLER-HAMMER MFG. CO., OF MILWAUKEE, WISCONSIN, A CORPORATION OF WISCONSIN.

IRONING APPLIANCE FOR SHOE-TREEING MACHINES.

1,325,022.

Specification of Letters Patent. Patented Dec. 16, 1919.

Application filed March 19, 1917. Serial No. 155,786.

To all whom it may concern:

Be it known that I, EDWIN N. LIGHTFOOT, a citizen of the United States, residing at New York, in the county of Bronx and State of New York, have invented new and useful Improvements in Ironing Appliances for Shoe-Treeing Machines, of which the following is a full, clear, concise, and exact description, reference being had to the accompanying drawing, forming a part of this specification.

This invention relates to ironing appliances for shoe treeing machines and more particularly to those employing electricity for heating.

It has heretofore been proposed to provide treeing irons with electrical heating elements and to connect the irons in circuit by cords as in the case of laundry irons. Much difficulty has, however, been experienced in providing an electrically heated iron sufficiently rugged to withstand the exceedingly hard usage met with in such service and it has been found that cord connections for such irons are very impracticable. The cords interfere with the use of the iron and are so frequently injured by carelessness of the user as to be an almost constant source of trouble and expense.

The present invention has among its objects to provide a convenient, safe and compact treeing iron appliance obviating the necessity for cord connection of the iron and to provide a more rugged and durable iron, wherein the electrical elements are protected against deterioration due to accident or rough usage.

Other objects and advantages will hereinafter appear.

In the accompanying drawing, wherein is illustrated an embodiment of the invention,

Figure 1 is a side elevational view of the appliance;

Fig. 2 is a longitudinal section through the treeing iron;

Fig. 3 is an enlarged transverse section substantially on line 3—3 of Fig. 2;

Fig. 4 is a similar view substantially on line 4—4 of Fig. 2;

Fig. 5 is a view similar to Fig. 1 but with the cover of the inclosed part of the appliance removed and showing certain of the inclosed parts sectioned;

Fig. 6 is a longitudinal sectional view substantially on line 6—6 of Fig. 7 looking in the direction of the arrows;

Fig. 7 is a transverse sectional view substantially on lines 7—7 of Figs. 5 and 6 also looking in the direction of the arrows;

Fig. 8 is a diagrammatic view showing the electrical connections employed in the three preceding figures.

Referring to the drawing, the appliance includes an electrically heated treeing iron 1 and a stand 2 to receive and support said iron, said stand being provided with suitable line connected contacts adapted to be engaged by coöperating contacts on said iron for heating the latter, said stand being further provided with suitable circuit controlling and current regulating elements.

Referring particularly to Figs. 1 to 4, the treeing iron includes a longitudinally bored metallic body 3 of usual exterior dimensions and contour, a heating element 4 located within the bore thereof, a metallic core 5 located inside said heating element and a pair of operative handles 6, 7 connected to said iron in spaced relation thereto.

The heating element 4, which is essentially of the type disclosed in my copending application, Serial No. 61,654, filed Nov. 15, 1915, is of hollow cylindrical form and adapted to fit snugly within the bore of the body 3 while the core 5 likewise fits snugly within the said heating element whereby dead space within the iron is eliminated and the heating element is maintained in intimate contact with the mass to be heated.

The core 5 is provided with an annular shoulder 8 which snugly engages within the bore of the body 3 and in practice is preferably welded thereto in flush relation with the end thereof to form a rigid and waterproof joint therewith. The outer end of said core projects an appreciable distance beyond the end surface of said iron to form a stop as hereinafter described, while the projecting end of the core is bored out and

screw threaded to receive a rod 9 to which the handle 6 is secured by means of a pin, said handle and supporting means being independent of the electrical connections for said iron.

A substantially elliptical plate 10 having

a centrally located bore therein is inset flush with the opposite end of the body 3 and rigidly secured thereto by means of screws 11 to form therewith a rugged but readily releasable joint. A tubular member 12 is welded or otherwise secured within the bore of the plate 10 and extends outwardly from said body portion while a metallic ring 13 is welded about the tube 12 substantially at its middle portion.

10 A cylindrical insulating fiber block or plug 14 having a reduced end portion 15 and being otherwise of the same external diameter as the tube 12 is attached to the latter by having its reduced end inserted therewithin and secured thereto by means of a pin 16. The handle 7, which is hollow throughout its length, and provided at its inner end with a rigidly anchored ferrule 17, is telescopically fitted over the outer end of said block 14 and tube 12 and secured to the latter by means of screws 18 passing through the ferrule 17 and entering the ring 13. By the above described construction, an exceedingly rugged and substantially waterproof attaching means for the handle 7 is also provided.

15 Lead wires 19, 20 for the heating element 4 extend therefrom and inside the tube 12 and handle 7, said wires passing through an insulating washer 21 located between the heating element 4 and the inner end of said tube and thereafter passing within an insulating tube 22 located within the tube 12, an insulating barrier 23 located within said inner tube serving to separate said wires passing therethrough.

20 The insulating block 14 is provided with longitudinally extending grooves or channels 24, 25 to receive said wires, the channel 25 extending the entire length of the said block and the channel 24 terminating a short distance from the outer end thereof.

25 The wire 20 is attached by means of a screw 26 to a projecting terminal contact 27 which is screwed within the outer end of the block 14 while the wire 19 is soldered or otherwise attached to a conducting plate 28 inset within the said block at the end 50 of the channel 24. An annular terminal contact 29 snugly engages the outer end of the handle 7 but in spaced relation to the contact 27, said collar being electrically connected with the plate 28 by means of a screw 30 passing through said contact and the adjacent portion of said handle and entering said plate, thus serving to electrically connect the terminal contact with the wire 19.

30 The employment of the tube 12 in the relation described is of importance since in addition to providing an inclosure for the heating element leads, the tubular construction furnishes the requisite mechanical strength and rigidity with a minimum

amount of metal, thus reducing to a minimum the conduction of heat to the handle 7. The portion of the said tube between the plate 10 and the ring 13 is preferably flattened to the approximate diameter of the 70 inclosed insulating tube 22, and in the plane of greatest breadth of the body 3 thus rendering this portion of the device more readily conformable to the surface to which the iron is applied in operation.

75 The heating stand 2 includes a terminal box 31 having an opening 32 to receive the handle 7 of the treeing iron and to support the same with its contacts in engagement with the line connected contacts located 80 within said box, said box being mounted upon a bed plate 33 which is upbent at its free end to form a supporting bracket 34 for the opposite end of the treeing iron. The upper end of the bracket 34 is bifurcated at 35 to receive the rod 9 and provides a positive support therefor, while the stop on the core 5 is adapted to abut the inner face of the bracket 34 for maintaining the aforesaid coöperating contacts in forcible engagement.

45 When the treeing iron is placed upon the stand with the handle 7 inserted in the opening 32, the conductive collar 29 rests upon a line connected contact 36 which comprises 95 an angle bent conductive strip anchored at 37 to a fixed insulating block 38 and further secured thereto by a screw 39, said strip being provided with a screw line terminal 40.

50 A bored insulating block 41 resting 100 upon the contact 36 serves to support a line connected contact 42 which comprises an elongated and shouldered conductive plug having an enlarged flat contacting head 43 and being mounted for reciprocation within 105 a metallic tube 44 lying in the core of said block and secured therein by means of lock nuts 45, 46. A conductive terminal strip 47 having a screw terminal 48 is anchored at 49 within said block and further secured 110 thereto by being clamped inside the lock nut 45, which serves also to maintain said strip in electrical engagement with the tube 44, said strip being bored to circumengage said tube. A bored insulating plug 50 having a rigidly anchored ferrule 51 is axially secured to the tube 44 by screwing said ferrule thereupon, said plug constituting a guide for the reduced portion 52 of the contact 42 which extends through the bore 115 of the tube 44 and carries therebeyond a washer 53 held upon said extension by a suitable key. A helical spring 54 surrounds said reduced extension within the tube 44 and serves to maintain the contact in yielding engagement with the coöperating contact 27 of the treeing iron while a cage member 55 is interposed between said spring and the shouldered portion of said contact and surrounds said spring to maintain electrical con-

120

125

130

nection between members 42 and 44. The contacting head 43 is of such size as to insure engagement thereof by the contact 27 of the handle 7 whenever the latter is fully 5 inserted within the opening 32.

An insulating cover block 56 and similar side pieces 57 and 58 serve to complete the insulating housing surrounding the line connected contacts, said blocks being 10 cured together by means of bolts 59, 60. The terminal box 31, which surrounds the above described insulating housing, comprises a metallic casing 61 divided longitudinally into compartments 62 and 63 by an

15 integral partition 64 and having detachable face plates 65, 66 secured to the casing by suitable screws. The insulating housing for the line connected contacts is positioned within the compartment 62 adjacent the 20 opening 32 and secured to the partition 64 by the bolts 60, said compartment also containing a cut-out device 67 including protective fuse plugs 68, 69 screwed within an insulating base which is also secured to the 25 partition 64 by means of screws 70. Screw terminals 71, 72 and 73, 74 serve to connect the respective fuses with suitable conductors which are led within the terminal box through a bushing 75, while a second bushing 30 76 extends through the partition 64 whereby suitable conductors may be led within the compartment 63 for connection with a current regulating rheostat 77 located therewithin.

35 Said rheostat which is of well known construction, is secured to the partition 64 by means of spacing bolts 78 and serves to regulate the current supplied to the line connected contacts 36 and 42 and thereby to the 40 heating element of the treeing iron. A movable contactor arm 79 is pivoted to the rheostat body at 80 to coöperate with three fixed contacts 81, 82 and 83 whereby three steps of resistance are provided for regulating the 45 heat of the iron to a like number of degrees. An operating handle 84 for the contactor arm projects through a slotted opening 85 in the face plate 66 whereby said rheostat may be operated from outside the 50 terminal box.

Referring particularly to Fig. 8, the circuit of the appliance hereinbefore described extends from supply line L through switch S and fuse 69 to upper rheostat terminal 86 55 and through that portion of the resistance R determined by the rheostat setting to lower rheostat terminal 87, thence to the contact 36 and through the conductors and heating element of the treeing iron to the resiliently 60 mounted contact 42, returning through fuse 68 and switch S to line L'.

Thus the treeing iron may be readily plugged within the terminal box by means of its free handle and locked therewithin by 65 resting the said handle within the groove

of the supporting bracket. The contacts upon the iron are arranged to positively engage the line connected contacts within the box irrespective of the rotative position of the iron when placed upon the stand, although the said iron, owing to its shape, will tend always to assume the same position when so placed. When heated, the iron may also be readily removed from the stand by means of its free handle and applied to 70 the work in the usual manner, such operation, however, being entirely unimpeded by any conductor cord or other fixed connection.

What I claim as new and desire to secure 80 by Letters Patent is:

1. In an ironing appliance for a shoe treeing machine, the combination with a treeing iron having an electrical heating element embodied therein and having a handle provided with adjacent terminal contacts for said element, of a support for said iron having a socket portion into which the contact carrying handle of the iron may be plugged and having within said socket portion line connected contacts to be engaged by the terminal contacts of said handle whereby said iron may be heated when on said support, for subsequent use without 85 line connections.

2. In an ironing appliance for a shoe treeing machine, the combination with a treeing iron having an electrical heating element and having a handle provided with adjacent terminal contacts for said element, of a stand for said iron having a supporting part for the contact carrying handle of the latter and line connected contacts to be engaged by the terminal contacts of said handle, said stand further having a part to 90 hold said iron in a position thereon for forcible engagement of said contacts.

3. In an ironing appliance for a shoe treeing machine, the combination with a treeing iron having an electrical heating element embodied therein and having a handle provided with an end contact and a peripheral annular contact concentric with the former contact, of a stand for said iron having a socket portion to receive said contact carrying handle and having within said socket portion line connected contacts to be engaged by the contacts on said handle.

4. In an ironing appliance for a shoe treeing machine, the combination with a treeing iron having an electrical heating element embodied therein and having a handle provided with an end contact and a peripheral annular contact concentric with the former contact, of a stand for said iron having a socket portion to receive said contact carrying handle and having within said socket portion line connected contacts to be engaged by the contacts on said handle, certain of said engaging contacts being resilient 105 110 115 120 125 130

and said stand further having a part to retain said iron in a position thereon for forcible engagement of said contacts.

5. In an ironing appliance for a shoe treeing machine, the combination with a treeing iron having an electrical heating element embodied therein and provided at opposite ends with operating handles, one provided with adjacent terminal contacts for said element, of a stand for said iron having a socket portion to receive the contact carrying handle and a part to support the iron adjacent to its opposite end, said socket portion having line connected contacts for engagement with the contacts on said handle.

6. In an ironing appliance for a shoe treeing machine, the combination with a treeing iron having an electrical heating element embodied therein and provided at opposite ends with operating handles, one provided with terminal contacts for said element, of a stand for said iron having a socket portion to receive the contact carrying handle and a part to support the iron adjacent to its opposite end, said socket portion having line connected contacts for engagement with the contacts on said handle, certain of said engaging contacts being resilient and said supporting part of said stand affording an abutment for said iron whereby the latter may be secured in said socket portion of said stand for forcible engagement of said contacts.

7. In an electrically heated treeing iron, in combination, a body portion having a recess therein, an electrical heating unit mounted within the recess of said body portion, a hollow handle including an insulating grip fixed to said body portion, a terminal contact projecting from the end of said handle, a terminal contact surrounding said grip and electrical connections between said unit and said terminal contacts inclosed within said hollow handle.

45. 8. In an electrically heated treeing iron, the combination with a body portion recessed longitudinally from an end thereof, an electrical heating unit insertible into said body portion from the end thereof, a tubular member provided with an integral flange secured to the end of said body portion in a countersunk relation therewith to tightly close the recess containing said unit, a hollow handle grip telescopically fitting said tubular member and terminal leads for said unit extending therefrom through said tubular member and said hand grip.

9. In an electrically heated treeing iron, the combination with a body portion recessed longitudinally from an end thereof, an electrical heating unit insertible into said body portion from the end thereof, a tubu-

lar member provided with an integral flange secured to the end of said body portion in a countersunk relation therewith to tightly close the recess containing said unit, said tubular member being contracted for general conformation with the contour of said body portion.

10. In an electrically heated treeing iron, in combination, a body portion recessed longitudinally, an electrical heating unit insertible into said body portion from one end thereof, a tubular member provided with an annular flange secured to said body portion and forming a cap for the unit receiving opening therein, a hollow hand-grip telescopically fitting said tubular member, a plug for said hand-grip having conductor passages therein, terminal contacts for said unit, terminal leads from said unit passing through said tubular member and said plug to said terminal contacts and an inclosing sleeve for said leads arranged within said tubular member between said unit and said plug.

11. In an electrically heated treeing iron, in combination, a body portion, an electrical heating unit inclosed therein, a tube fixed to said body portion and providing a passage for the terminal leads from said unit, a member telescopically fitting said tube, said member having separate passages for said leads and contacts to be connected thereto, one of said contacts being fixed to the end of said member and another to the side thereof and a tubular hand-grip to telescopically fit said member and tube, said hand-grip having a contact in the periphery thereof and a screw to electrically connect the same with the side contact of said member.

12. In an electrically heated treeing iron, in combination, a body member recessed from end to end thereof, a member insertible into said body member from one end thereof to centrally occupy the recess within the latter, said members being welded together and said inserted member having an extended portion to support a hand grip, an electrical heating unit of tubular form insertible between said members from the opposite end of said body member and a hollow handle for said body member fixed to the end thereof to cap the unit receiving recess therein and to provide an outlet for the terminal leads of said unit.

In witness whereof, I have hereunto subscribed my name.

EDWIN N. LIGHTFOOT.
